UNITED STATES PATENT OFFICE.

JOHN S. CHAMBERS, OF NEW YORK, N. Y., ASSIGNOR TO CHAMBERS VALVE COMPANY,
OF NEW YORK, N. Y., A CORPORATION OF NEW YORK.

STEAM-BOILER.

1,250,091.

Specification of Letters Patent. Patented Dec. 11, 1917.

Application filed April 26, 1913. Serial No. 763,905.

To all whom it may concern:

Be it known that I, JOHN S. CHAMBERS, a citizen of the United States, and resident of the borough of Manhattan, in the city and State of New York, have invented a new and useful Improvement in Steam-Boilers, of which the following is a specification.

This invention comprises certain improvements in the construction, form and arrangement of certain portions of a steam boiler whereby ample room is left in the usual steam dome for ready and convenient access to the interior of the boiler and more steam space is provided within the boiler. These results are obtained by removing the stand-pipe and its throttle-valve from the main steam dome and moving the stand-pipe and throttle-valve to a point along the boiler near the front end thereof and providing the stand-pipe with its own auxiliary steam dome.

Practical embodiments of this invention are represented in the accompanying drawings, in which—

Figure 1 is a longitudinal vertical section through a portion of a steam boiler of the locomotive type with my invention applied thereto, the throttle and relief valves being shown closed.

Fig. 2 is a detail similar section showing the throttle and relief valves open, and

Fig. 3 is a view similar to Fig. 1 showing a modified form of the invention.

The boiler is denoted by 1, the main steam dome by 2 and its removable cap by 3. The stand-pipe is denoted by 4 and its auxiliary steam dome by 5. The combined steam dome and stand-pipe are preferably cast integral 40 and they are located in close proximity to the front end of the boiler. In Fig. 1 the combined steam dome and stand-pipe is located back of the flue sheet 6 and in Fig. 3 it is located in front of the said flue sheet.

A throttle valve seat 7 is provided at the upper end or mouth of the stand-pipe 4.

A throttle valve 8 of the piston type serves to open and close communication between the interior of the auxiliary dome 5 and stand-pipe 4, which throttle-valve slides within a piston chamber 9 formed by the depending annular flange 10 of the removable cap 11 of the auxiliary steam dome.

A relief valve 12 is arranged to open and close communication between the interior 55 of the stand-pipe 4 and the interior of the piston chamber 9 through the throttle valve 8. The throttle valve is provided with a centrally arranged passage 13 therethrough having a seat 14 for the relief valve 12. 60 A valve stem 15 is rigidly secured to the relief valve 12, which stem is slidably mounted in the hub 16 of the throttle valve. This stem 15 is further provided with an enlargement 17 slidably engaged with the 65 guides 18 depending from the throttle valve 8. These guides 18 have a sliding engagement with the inner walls of the stand-pipe 4 and therefore serve as guides for the throttle valve and also for the valve stem 70 15. The throttle valve is raised from its seat by the engagement of the enlargement 17 with the valve hub 16 after the valve stem has opened the relief valve 12 during the first part of the upward movement of 75 the valve stem.

The throttle and relief valves are under the control of a rock lever, the arm 19 of which is fast on the rock shaft 20, which shaft is connected to a throttle valve controlling means, not shown herein.

The removable cap 11 of the auxiliary dome 5 is provided with a removable plug 21 whereby access may be readily obtained to the relief valve 12 without the necessity 85 of removing the cap 11.

Steam is supplied to the auxiliary steam dome 5 from the top of the usual steam dome 2.

In the form shown in Fig. 1, the convey 90 pipe 22 leads downwardly from the top of the main steam dome 2 at one side thereof into the interior of the steam boiler 1 and from thence forwardly and upwardly through the shell of the boiler into the bottom of the auxiliary steam dome 5.

In this form the dry pipe 23 communicates with the stand-pipe 4 through the side of the auxiliary steam dome 5 and leads therefrom to the superheater or T-head not 100 shown.

In the form shown in Fig. 3 the convey pipe 22 leads from the top of the usual steam dome 2 at one side thereof downwardly into the interior of the boiler, thence forwardly 105 in close proximity to its top and from thence

upwardly through the boiler shell and forwardly into communication with the side of the steam dome 5.

In this form the dry-pipe 23 communicates with the stand-pipe 4 through the bottom of the auxiliary steam dome 5 and leads from said stand-pipe to the superheater or T-head, not shown.

In both of the forms shown, the portion 10 of the convey pipe 22 adjacent to its mouth 24 is flattened, as shown, at 25, to give more ready access to the interior of the boiler through the main steam dome 2.

The convey pipe 22 is further provided 15 near its mouth with a baffle plate 26 for preventing the water from being drawn into the convey-pipe with the steam.

In operation, when it is desired to open 20 the throttle-valve the first part of the upward movement of the valve stem will open the relief valve 12 and thereby release any built-up pressure in the piston chamber 9 due to the leakage of the steam past the throttle-valve into the said chamber. The 25 further upward movement of the valve stem will cause the enlargement 17 to engage the hub 16 and thereby open the throttle-valve.

By locating the stand-pipe outside of the 30 main steam dome, it will be seen that ample room is provided for gaining access to the interior of the boiler by removing the cap 3.

By casting the stand-pipe and its auxiliary steam dome integral, it will be seen that a very simple and strong structure is 35 provided.

It will also be seen that a novel construction, arrangement and operation of the throttle valve is obtained in which the parts are readily accessible.

40 It is evident that changes might be resorted to in the form, construction and arrangement of the several parts without departing from the spirit and scope of my invention; hence I do not wish to limit myself 45 strictly to the structure herein set forth, but

What I claim is:—

1. The combination with a steam boiler, of a steam dome provided with a removable cap having a piston chamber therein, a 50 stand-pipe and a throttle-valve of the piston type therefor slidable in said piston chamber.

2. The combination with a steam boiler, of a steam dome provided with a removable 55 cap having a piston chamber therein, a stand-pipe and a throttle-valve of the piston type therefor slidable in said piston chamber and having guiding means engaging the stand-pipe.

60 3. The combination with a steam boiler, of a steam dome having a piston chamber therein, a stand-pipe, a throttle valve of the

piston type therefor slidable in said piston chamber and a relief valve for said piston chamber.

65

4. The combination with a steam boiler, of a steam dome having a piston chamber therein, a stand-pipe, a throttle-valve of the piston type therefor slidable in said piston chamber and having guiding means engaging the stand-pipe and a relief valve for said piston chamber.

70

5. The combination with a steam boiler, of a steam dome having a piston chamber therein, a stand-pipe, a throttle-valve of the piston type therefor slidable in said piston chamber and having guiding means engaging the stand-pipe, a relief valve for said piston chamber and a valve stem slidably mounted in the throttle-valve and its guiding means, arranged to first open the relief valve and then the throttle-valve during its movement in one direction, and means for operating the valve stem.

75

6. The combination with a steam boiler, of a steam dome, provided with a removable cap having a piston chamber therein, a stand-pipe, a throttle-valve of the piston type therefor slidable in said piston chamber and a relief valve for said piston chamber.

80

7. The combination with a steam-boiler, of a steam dome provided with a removable cap having a piston chamber therein, a stand-pipe, a throttle-valve of the piston type therefor slidable in said piston chamber and having guiding means engaging the stand-pipe and a relief valve for said piston chamber.

85

8. The combination with a steam boiler, of a steam dome having a piston chamber therein, a stand-pipe, a throttle-valve of the piston type therefor slidable in the piston chamber, a relief valve for said piston chamber and a removable plug in the dome for gaining access to the relief valve.

90

9. The combination with a steam boiler, of a steam dome provided with a cap having a piston chamber therein, a stand-pipe, a throttle valve of the piston type therefor slidable in said piston chamber, a relief valve for said piston chamber, a removable plug in said cap for gaining access to the relief valve, said cap being removable for gaining access to the throttle-valve.

115

In testimony, that I claim the foregoing as my invention, I have signed my name, in presence of two witnesses, this eleventh day of March, 1913.

JOHN S. CHAMBERS.
